UNITED STATES PATENT OFFICE.

EDWARD R. DOWNE, OF LARCHMONT, NEW YORK, ASSIGNOR TO AMERICAN RADIATOR COMPANY, OF NEW YORK, N. Y., A CORPORATION OF NEW JERSEY.

GAS BOILER.

Application filed September 30, 1925. Serial No. 59,442.

My invention relates to improvements in heating apparatus, and the same has for its object more particularly to provide a simple, efficient and reliable boiler in which the water or other medium circulating through the same is heated by the hot gases and products of combustion resulting from the burning of a gaseous or other fuel.

Further, said invention has for its object 10 to provide a boiler in which a relatively large amount of the heat resulting from the combustion of said fuel is efficiently absorbed by the water or other circulating medium in the boiler.

15 Further, said invention has for its object to provide a boiler in which the heat absorbing surfaces thereof are such as to efficiently transfer to the circulating medium of the boiler the maximum amount of heat said circulating medium is capable of acquiring or absorbing.

20 Further, said invention has for its object to provide a boiler having a minimum of heat absorbing surfaces in intimate contact 25 with the hot gases and products of combustion passing through the flues of the boiler at high velocity, and in which said heat absorbing surfaces efficiently transfer the heat acquired thereby to the circulating medium 30 within the boiler.

Further, said invention has for its object to provide a boiler in which a large number of relatively small projections or heat absorbing elements are distributed over the 35 walls of the flue or flues thereof in vertically staggered relation and extend into the path of the hot gases and products of combustion passing through the flue at high velocity in intimate and effective contact therewith.

40 Further, said invention has for its object to provide a boiler in which the sections thereof may be readily assembled to form the flues without the heat absorbing elements or projections interfering with the proper alignment and registry of said sections.

45 Further, said invention has for its object to provide a boiler in which the hot gases and products of combustion as the same enter the flue or flues are subjected to Venturi-like 50 action to cause said gases and said products of combustion to spread or fan out laterally before the same engage with the projections or heat absorbing elements throughout the entire area of the flue.

Further, said invention has for its object 55 to provide a boiler in which the transverse flue area thereof is greater at the inlet than at the outlet of the flue, and in which the free transverse flue area provided between the heat absorbing elements is less than the corresponding area of the inlet and greater than the corresponding area at the outlet of said flue, whereby to provide a flue diminishing upwardly in transverse area in accordance 60 with the decrease in temperature of the gases and products of combustion as the same pass towards the outlet of the flue.

Further, said invention has for its object 65 to provide a boiler in which the projections or heat absorbing elements extending into the path of the hot gases and products of combustion passing through the flues provide with the walls of the flue an extended surface area so proportioned as to abstract 70 from the hot gases and products of combustion substantially the maximum amount of heat capable of being absorbed by the circulating medium within the boiler and to transfer the same thereto, and in which said projections or heat absorbing elements are so 75 spaced as to permit of the said hot gases and products of combustion passing through said flues at relatively high velocity.

Further, said invention has for its object 80 to provide a boiler in which relatively small, solid, heat absorbing projections or elements are distributed in sufficient numbers over the walls of the flue to provide a relatively large absorbing surface per unit of water backed 85 surface, and to maintain the transverse flue area between the same sufficiently large to 90 permit of the hot gases and products of combustion passing through the flue at relatively high velocity.

Further, said invention has for its object 95 to provide a boiler in which the relatively small, solid projections are arranged in rows upon the walls of the flue or flues to provide spaces between adjacent rows adapted to receive an instrument to permit of the 100 entire surface of said projections being cleaned.

Further, said invention has for its object 105 to provide a boiler in which a plurality of relatively small projections are distributed over the walls of the flue and extend into the path of the hot gases and products of combustion passing therethrough, and in

which the dimensions of each of said projections are such as to permit of the proper transmission therethrough to the circulating medium of the heat absorbed by said projections.

- Further, said invention has for its object to provide a boiler in which a large number of relatively small projections or heat absorbing elements are disposed upon the walls of the flue or flues and extend into the path of the hot gases and products of combustion passing therethrough, and in which the length of each projection is less than or not greater than twice the average diameter thereof.
- Further, said invention has for its object to provide a boiler of the character specified which shall be compact in form, and occupy about one half of the volume ordinarily occupied by solid fuel burning boilers possessing the same rating.

Other objects will in part be obvious, and in part be pointed out hereinafter.

To the attainment of the aforesaid objects and ends, my invention consists in the novel details of construction, and in the combination, connection and arrangement of parts hereinafter more fully described and then pointed out in the claims.

In the accompanying drawings showing an illustrative embodiment of the invention—

Figure 1 is a front elevation showing one form of boiler constructed according to and embodying my said invention;

Fig. 2 is a side elevation thereof;

Fig. 3 is a vertical section on the line 3—3 of Fig. 4;

Fig. 4 is a vertical section thereof on the line 4—4 of Fig. 3;

Fig. 5 is an elevation of one face of a boiler section;

Fig. 6, is a vertical section thereof on the line 6—6 of Fig. 5;

Fig. 7 is an enlarged detail face view showing the arrangement of the heat absorbing elements or projections shown at Fig. 5; and,

Fig. 8 is an enlarged detail sectional view taken on the line 8—8 of Fig. 7.

Referring to the drawings, the boiler comprises hollow end sections 11 and 12, and a plurality of hollow intermediate sections 13. The end sections 11 and 12 extend downwardly below the intermediate sections 13 to provide pedestals or supports 14 on which the boiler rests and to provide a combustion chamber 15 below the sections 13. In the combustion chamber 15 is located suitable heating means, such as gas burners 16.

The sections 11, 12 and 13 are provided with three series of alined openings 17, 17^a and 17^b within which are secured the nipples 18 in order to hold said sections in assembled relation, and to permit of the circulation of heating fluid throughout the boiler.

The series of openings 17 and 17^a are arranged at the bottom at opposite sides of the

boiler or sections, and the series of openings 17^b is arranged at the top of the sections centrally thereof.

The assembled sections of the boiler are preferably enclosed by an insulating jacket 19. The jacket 19 has an opening 20 therein at the front to permit access to the combustion chamber 15, and said opening 20 is closed by a suitable frame or closure 21 through which the gas pipes or burner tubes 22 to the burner 16 and the pilot line 23 pass. The burner tubes 22 and pilot light 23 are supplied with gas from the manifold 24 which is controlled by a suitable gas governor 25, and by a snap valve 26 adapted to be actuated through the connections 27 by the usual thermostatic or pressure responsive regulator. The frame 21 has sight openings 28 therein. Baffle plates 29 are disposed horizontally between the pedestals 14 at the front and rear of the burners 16.

Above the combustion chamber 15 the successive sections are in spaced relation to each other to provide between them a plurality of vertical flues 30 through which the hot gases and products of combustion from the combustion chamber may pass and contact with the heat absorbing surfaces of the sections to heat the water therein. The flues 30 are open at the top and discharge the gases or products of combustion into a chamber or smoke hood 31 having a stack or outlet 32.

The several sections are maintained in spaced relation to form said flues 30 by means of the integral marginal flanges 33 and the hubs or nipple ports 34 and 34^a registering with each other at their opposing edges.

Distributed over the opposing walls of the flues 30 are a plurality of horizontal rows 35 of relatively small tapering projections or heat absorbing elements 36. The projections are preferably cast integrally with the sections upon both sides of the section 13 and upon one side of the sections 11 and 12, and said projections are substantially solid.

The projections 36 are slightly shorter than the width of the marginal flanges 33 to permit of the sections being evenly engaged at the margins and at the ends of the hubs 34 and 34^a. Each row of projections 36 is arranged in horizontal alinement with a corresponding row upon the opposing wall of the flue 30, and the corresponding opposing projections are spaced at their adjacent ends, as indicated at 37, whereby the entire surface of each projection is exposed to the hot gases and products of combustion passing through the flues 30. The projections 36 of each row are also staggered relative to the projections of the adjacent rows above and below the same. The flanges 33 are interrupted at one side of the boiler to provide an opening 38 to each flue through which a suitable instrument or brush may be inserted into the horizontal spaces 39 between the rows 35 for cleaning the pro-

jections 36. As these projections have very small diameters substantially the entire exposed surface thereof may be readily cleaned by the operation. The openings 38 are normally closed by suitable closures or covers 40, (Fig. 5) and secured in position by screws 40^a and a thumb nut 40^b. Each screw 40^a has a hook 40^c at its inner end engaging certain of the projections 36 on the boiler sections 13.

The number of projections 36 extending into the path of the hot gases and products of combustion is sufficiently large to permit of said projections and the walls of said flue 15 absorbing from the said gases and products of combustion, and transmitting to the circulating medium the maximum amount of heat which the circulating medium or water within the boiler is capable of absorbing.

20 In the boiler embodying my said invention a relatively large heat absorbing area per unit of water backed surface is provided, in order to insure the absorption by the circulating medium of the maximum amount of heat, 25 without unduly restricting the free transverse flue area between the projections, and, thus permit the hot gases and products of combustion to pass through said flues at a high velocity in intimate and effective contact with the 30 heat absorbing surfaces thereof. The result is obtained by providing a large number of very small projections 36 and disposing the same upon the opposing walls of the flue without unduly retarding the flow of the hot gases 35 and products of combustion. In practice, the length of each projection 36 should not exceed twice the average diameter thereof to insure the proper transmission of heat from the hot gases through the projection to the 40 water or circulating medium within the boiler. The cross sectional area of the projection at the base thereof, which represents the metal through which the heat has to be transferred, is approximately one fourth of the area of the 45 total external or exposed surface of said projection. In order to effect the efficient transfer of heat from the hot gases to the circulating medium, the projections of each horizontal row 35 should preferably be spaced 50 from each other a distance equal to or slightly exceeding the maximum diameter of the individual projection. The construction and arrangement of the projections 36, as herein-described, serves to divide each flue into a 55 series of uninterrupted vertical passages 36^a, each of whose area in cross-section is relatively wide at its intermediate portion 36^b, and tapers towards the opposite ends 36^c thereof, as shown at Figs. 7 and 8.

60 The inner adjacent curved surfaces 41 of the hubs 34 form a constricted inlet to each flue, providing a Venturi-like entrance portion which causes the hot gases and products of combustion, as the same enter said flue, to 65 spread or fan out laterally and to pass

through the flue in intimate contact with all of the staggered projections throughout the width of said flue.

As shown at Fig. 6, the lower portion 42 of each flue 30 is wider than the upper portion 70 thereof to provide a transverse flue area at the entrance or inlet thereof ample to permit of the passage of all of the highly heated gases and products of combustion into the flue. The outlet 43 of the flue, restricted by the hubs 75 34^a, has a transverse flue area less than that of said inlet 42. The free intermediate flue area between the heat absorbing projections 36 is less than the corresponding area at the inlet and greater than the corresponding area 80 at the outlet of the flue, the transverse flue area diminishing in accordance with the decrease in temperature of the gases and products of combustion as the same pass towards said outlets 43.

85 In operation the gases pass at high velocity through the flue 30 in fine streams in intimate contact with the projections 36 and the walls of the flues. By the time said gases reach the top of the boiler the maximum amount of 90 heat has been abstracted therefrom and transferred to the water or circulating medium.

In actual use of a boiler embodying the invention it has been ascertained that the gases entering the flues with a temperature of about 95 2000° F. and after passing through said flues to the outlet surrendered about 1700° F. of heat during the travel through said flues consuming about 1/6 second, and indicated a temperature of about 300° F. upon emerging 100 from the outlets of said flues.

By applicant's invention about 86% of all the heat available in the gas is utilized.

The heated circulating medium may be employed for industrial hot water supply, auxiliary low pressure steam, house heating and other purposes. The openings 44 are supply tappings and the openings 45 are return tappings. The openings 44 and 45 at either side of the boiler may be connected to the circulating heating system for supplying heating fluid to radiators or other heat emitting apparatus. The openings 44 and 45 not in use may be sealed with suitable closures 46.

105 I have found, for example, that satisfactory results may be obtained by a construction in which said hollow section may be approximately 20 inches wide, 30 inches high and 3 inches thick. In the assembled boiler of that size the distance between the central portions 110 of the opposing walls of each flue is 1 inch. The transverse flue area at the bottom of each flue just above the burner is about 30 square inches. The corresponding area at 115 the top of each flue on a line with the center of the upper nipple part is 13.5 square inches. The corresponding flue area between two opposing rows of projections averages 120 16.5 square inches. The height of each projection 36 is 0.4375 inches; the diameter at 125

the base of the projection 0.3175 inches; the average diameter of the projection 0.2525 inches; the external or exposed surface of the projection 0.3277 square inches; the area covered by the base of the projection 0.0791 square inches; the distance horizontally between projections (center to center) is .75 inches, and the distance vertically between the same is 1 inch. The proportionate amount of outer wall surface for each projection is a rectangle 1 inch by .75 inches. A unit of outer wall surface, therefore, will consist of such rectangle of .75 square inches, less the area of the base of one projection .0791 thus leaving .6709 square inches, plus .3277 square inches, the external surface of the projection, while a corresponding area or unit of inner wall surface will be merely a rectangle 1 inch by .75 inches equaling .75 square inches.

20 The ratio of outer to inner surface will, therefore be $\frac{.9986}{.75}$ or 1.33.

Having thus described my invention what I claim and desire to secure by Letters 25 Patent is;

1. A boiler of the character described comprising a plurality of water containing sections forming flues therebetween, and a plurality of relatively small tapering projections distributed over the opposing walls of said flues and extending into the path of the hot gases and products of combustion passing therethrough, and serving to divide each flue into a series of uninterrupted vertical passages, each of whose area in cross-section is relatively wide at its intermediate portion and tapering towards the opposite ends thereof; and in which the ratio of a rectangular area of said flue wall whose sides are tangent to the outermost rows of projections, together with the area of its said projections, is about 1.33 times the area of the corresponding rectangular area of inner wall surface, substantially as specified.
- 45 2. A boiler of the character described comprising a plurality of water containing sections forming flues therebetween, and a plurality of relatively small tapering projections distributed over the opposing walls of said flues and extending into the path of the hot gases and products of combustion passing therethrough and serving to divide said flue into a series of uninterrupted vertical passages, each of whose area in cross-section is relatively wide at its intermediate portion and tapering towards the opposite ends thereof, and in which the ratio of the exposed area of one of said projections and its proportionate amount of surrounding wall surface is about 1.33 times the area of a corresponding unit of inner wall surface, substantially as specified.
- 55 3. A boiler of the character described comprising a plurality of water containing sections forming a relatively narrow flue there-

between, and a plurality of relatively small projections distributed over the opposing walls of said flue in staggered relation and extending into the path of and entirely exposed to the hot gases and products of combustion passing therethrough, and spaced laterally from one another a distance slightly greater than the maximum diameter thereof to divide said flue into a series of uninterrupted vertical passages to permit of the flow of the hot gases and products of combustion through said flue at such velocity to insure the maximum absorption of heat by the contents of the boiler; and in which the ratio of a unit of outer wall surface of that part lying within an outline coinciding substantially with the outermost of the projections extending from said flue wall together with the exposed area of said projections, ranges from 1.2 to 1.5 times the area of a corresponding unit of inner wall surface, substantially as specified.

4. A boiler of the character described comprising a plurality of water containing sections forming a relatively narrow flue therebetween for the passage of the hot gases and products of combustion, and a plurality of relatively small, tapering, solid projections distributed over the opposing walls of said flue and extending into the path of the hot gases and products of combustion passing therethrough, and serving to divide said flue into a series of uninterrupted vertical passages each of whose area in cross-section is relatively wide at its intermediate portion and tapering towards the ends thereof and whose longer axis is disposed at right angles to the plane of said flue, substantially as specified.

5. A boiler of the character described comprising water containing sections forming a flue therebetween, and a plurality of relatively small solid projections extending from the wall of said flue into the path of the hot gases and products of combustion passing therethrough; each of said projections having a cross sectional area at the base thereof which is approximately one quarter of the area of the entire exposed surface thereof, substantially as specified.

6. A boiler of the character described comprising a plurality of water containing sections forming a flue therebetween, and a plurality of relatively small substantially solid projections extending from the walls of said flue into the path of the hot gases and products of combustion passing therethrough; each of said projections having a length greater than the average diameter thereof and less than twice said diameter, and having a cross sectional area at the base thereof which is approximately one quarter of the area of the entire exposed surface thereof, substantially as specified.

7. A boiler of the character described com-

- prising a plurality of water containing sections forming a flue therebetween, and a plurality of rows of relatively small projections extending from the wall of said flue into the path of the hot gases and products of combustion passing therethrough; the projections of each row being spaced from one another a distance slightly greater than the maximum diameter thereof and being arranged to form a series of vertical flues whose area in cross-section is relatively wide at its intermediate portion and tapering towards its opposite ends, substantially as specified.
8. A boiler of the character described comprising a plurality of water containing elements forming a flue therebetween, and a plurality of rows of relatively small solid projections extending from the walls of said flue into the path of the hot gases and products of combustion passing therethrough; the projections of each row being spaced from one another a distance slightly greater than the maximum diameter thereof and being staggered relative to the projections of the adjacent rows at opposite sides thereof, substantially as specified.
9. A boiler of the character described comprising a plurality of water containing sections forming a vertical flue therebetween, and a plurality of horizontal, parallel rows of relatively small solid projections extending from the opposing walls of said flue into the path of the hot gases and products of combustion passing therethrough; said projections each having a length greater than the average diameter thereof and less than twice said diameter; and the projections of

each row being spaced from one another a distance slightly exceeding the maximum diameter thereof, and being staggered relative to the projections of the adjacent rows at opposite sides thereof and being arranged to form a series of vertical flues whose area in cross-section is relatively wide at its intermediate portion and tapering towards its opposite ends, substantially as specified.

10. A boiler of the character described comprising a plurality of water containing elements forming a flue therebetween, and a plurality of rows of relatively small solid projections extending from the opposing walls of said flue into the path of the hot gases and products of combustion passing therethrough; the projections of each row being arranged in alinement with and in spaced relation to the corresponding projections of the opposing row, and being spaced from one another a distance slightly exceeding the maximum diameter thereof, and being staggered relative to the projections of the adjacent rows at opposite sides thereof; each of said projections having a length greater than the average diameter thereof and less than twice said diameter, and having a cross sectional area at the base thereof which is approximately one quarter of the area of the entire exposed surface thereof, substantially as specified.

Signed at the city of New York, in the county and State of New York, this twenty-eighth day of September, one thousand nine hundred and twenty-five.

EDWARD R. DOWNE.
